UNITED STATES PATENT OFFICE.

GEORGE A. LOWREY, OF BALTIMORE, MARYLAND.

GAME-BOARD.

1,321,464.

Specification of Letters Patent. Patented Nov. 11, 1919.

Application filed July 18, 1917. Serial No. 181,284.

To all whom it may concern:

Be it known that I, GEORGE A. LOWREY, a citizen of the United States, residing at Baltimore, in the State of Maryland, have 5 invented certain new and useful Improvements in Game-Boards; and I do hereby declare the following to be a full, clear, and exact description of the invention, such as will enable others skilled in the art to which 10 it appertains to make and use the same.

My invention relates to game-boards.

One object of my invention is to produce 15 a game-board having a surface laid out in the similitude of the ordinary baseball diamond and provided with a plurality of fixed figures thereupon representing a baseball team constituting the "outs."

Another object of my invention is to provide 20 a plurality of normally hidden figures representing the "ins" which shall be revealed to view when certain pre-determined conditions are fulfilled.

Another object of my invention is to provide 25 visible means under control of the person playing the game for causing the appearance of the "ins" when certain pre-determined conditions are fulfilled.

A further object of my invention is to provide 30 means under the control of the operator of the game for causing the disappearance of the "ins" when a certain round of play is finished.

These and further objects of my invention will be described and explained in the 35 accompanying specification and pointed out in the claims, reference being had to the accompanying drawing, of which:

Figure 1 is a plan view of my improved game board.

Fig. 2 is a side view thereof.

Fig. 3 is an enlarged view of some of the parts shown in Fig. 2, looking in the direction of the arrow 3 in said figure.

Fig. 4 is a view of the parts shown in 45 Fig. 3 looking in the direction of the arrow 4 in said figure.

Fig. 5 is an enlarged view of one of the means for holding a figure belonging to the "ins" looking in the direction of the 50 arrow 5 in Fig. 1.

Fig. 6 is a view of the parts shown in Fig. 5 looking in the direction of the arrow 6 in said figure.

Fig. 7 is an enlarged view of the means 55 for resetting the ball, hereinafter described.

Fig. 8 is an enlarged view of one of the

tripping mechanisms for operating a figure belonging to the "ins" when viewed in the direction of the arrow 8 in Fig. 1.

Fig. 9 is a view of the parts shown in 60 Fig. 8 looking in the direction of the arrow 9 in said figure.

Fig. 10 is an enlarged view of certain details hereinafter described.

In carrying out my invention I provide 65 a framework 15 formed of a plurality of vertical pipe sections such as 16, each provided with a flange 17 forming a foot therefor.

Each of the pipe sections 16—16 at the 70 front and rear of my improved game board is joined at its top by means of an elbow such as 18 with a horizontal pipe section such as 19, and the inner ends of the sections 19 are joined together by the two arms of 75 the cross connection 20. The horizontal pipe sections such as 21—21 are threaded into the remaining arms of the cross section and the outer ends of the pipe sections 21—21 are joined by means of the elbows 22—22 80 with the vertical pipe sections 16—16 at the sides of my improved game board.

The metallic frame provided, as just described, supports a framework preferably 85 formed of wood, said framework comprising the front end piece 23, the rear end piece 24, the parallel side pieces 25—25 and the oblique side pieces 26—26. Between the ends of the parallel side pieces 25—25 and the oblique side pieces 26—26, the cross 90 piece 27 is provided and additional cross pieces 28, 29 and 30 are provided between the front end piece 23 and the cross piece 27, and cross pieces 31, 32, 33 and 34 are also provided between the rear end piece 24 and 95 the cross piece 27.

The front end piece 23 and the cross pieces 27 and 28 are united with the parallel sides 25—25 by metallic knee pieces such as 35, and the rear end piece 24 and the cross 100 piece 27 are united with the oblique pieces 26—26 by metallic knee pieces such as 36. The cross pieces 29 and 30 are secured to the parallel side pieces 25 by screws such as 37, and the cross pieces 31, 32, 33 and 34 are 105 secured to the oblique pieces 26—26 by screws such as 38.

The framework, bounded by the front end 23, rear end 24, parallel side pieces 25—25 and oblique side pieces 26—26, is secured to 110 the metallic framework by screws such as 39.

The framework formed by the front end

piece 23, the rear end piece 24, the parallel side pieces 25—25 and the oblique side pieces 26—26 is provided with a suitable cover 40 having laid out thereupon a baseball diamond 41, and said covering is extended over the edges of said front, rear and said side pieces backwardly nearly to the feet 17, forming a curtain 42 to shield the interior mechanisms of my improved game 10 board from view.

Rectangular holes such as 43, 44, 45 and 45^a are provided in the cover 40 at the locations, respectively, of the first, second, third and home bases of the baseball diamond 41. One 15 of these holes is shown enlarged in Fig. 10, and it is formed by cutting a rectangular hole, provided with flaps, in the cover 40, turning said flaps around the wire frame 46 and securing said flaps on the underside of 20 the cover 40 by a line of stitches such as 47.

There are affixed to the cover 40 a plurality of figures such as 48, representing the ball team having the "outs" and located in the positions usually occupied by the members of the "out" team. The umpire 49 is also fixed in position.

51 represents a member of the "in" team who has reached first base, and 52, 53 and 50 respectively, represent members of the 30 "in" team who have reached second, third, and home bases, respectively, and these figures will hereinafter be referred to as base runners. Base runners 50, 52 and 53 are normally hidden from view, as shown in 35 Figs. 1 and 2, but they are supported in such a manner that they will be brought into view as is the base runner 51 in Fig. 2 as hereinafter explained.

Each of the base runners 50, 51, 52 and 53 40 is mounted upon a base 54 (see Figs. 5 and 6) and the base is secured to a support 55. The support 55 is united to the counter-balance 56 by means of the cross pieces 57—57 and screws such as 58, and the whole structure thus formed, including the base runner attached to the base 54, revolves freely upon the bolt 59, the latter being secured in the distance block 60 and the side frame 25, and a nut such as 61 retains said parts in position upon the bolt 59.

The counter-balance 56 is made of such a weight that the parts connected thereto, including the base runner, will have a normal tendency to assume the position shown in 55 Figs. 5 and 6 and said parts are moved by the operator from said position to the position shown in Fig. 2 whenever the game is to be set to be played.

The instrumentalities by which the base 60 runners are moved from the position shown dotted in Fig. 2 to the position shown by full lines in Figs. 5 and 6 will now be described.

A block such as 62 is secured by means of 65 the screws 63 and the nuts 64 to the front

end piece 23, said block being provided with a hole in which is slidably mounted a metallic pipe 65, the other end of the metallic pipe being supported and sliding freely in the guide 66, which is secured by means of 70 the screws 67 to the cross piece 28. On the front end of the pipe 65 is screwed a T piece 68 and short pieces of pipe 69 are threaded into the cross piece of said T.

Strips of cloth, rubber, leather or any 75 other suitable materials are wound around the pipe 65, the T 68 and pipe 69 to form a fairly elastic ball, and said ball is provided in any approved manner with a leather covering, the whole forming a striking buffer 80 70. A collar 71 is secured upon the pipe 65 and a spring 72 is loosely mounted upon said pipe between the collar 71 and the front of the block 62.

The inner end of the pipe 65 is threaded and provided with two nuts 72—72 between which is clamped the ear 73. One end of the belt 74 is secured to the ear 73 and said belt extends around the pulley 75 and is secured thereto by screws such as 76. A 90 spring 77 is secured to the pulley 75 by means of the screw 78 and said spring serves to keep the buffer 70 in the position shown in Figs. 2 and 4.

The pulley 75 is secured to the flanges 95 80—80 and said flanges are secured to the shaft 81 by means of the pins 82—82. A bearing block 83 is secured to the supporting strips 84—84 by means of screws such as 85 and the supporting strips are secured to the 100 front end piece 23 and the cross piece 28 by screws such as 86. Flanges such as 87—87 are secured to the bearing block 83 by means of bolts 88 and a pipe 89 is rigidly secured in the flanges 87. The shaft 81 extends 105 through the pipe 89 and on the upper end of said shaft the flanges 90 are rigidly secured. Between the flanges 90 the bat 91 is secured by means of the bolts 92. The bearing block 83 is placed somewhat toward the left of the center of the game board and to the left of the pipe 65 and said bat extends toward the right to somewhat beyond the center of the game board and is provided with a slot 93 closed by the end piece 94, 110 which strikes the wire 95 and limits the movement of the bat 91.

A ball guide wire 95 extends through the slot 93 and passes through the front and rear vertical pipe sections 16 and the ends 120 of said wire are threaded and said wire is placed under a suitable longitudinal stress by means of the nuts 96 threaded upon the ends thereof. The ball 97, preferably of wood, slides freely upon the wire 95.

The means by which the motion of the ball 97 causes the figures 50, 51, 52 and 53, representing the members of the "in" team, to appear at the bases during the progress 125 of the game will now be described.

Since each of the base runners 50, 51, 52 and 53 is operated in the same way, the means for operating but one base runner will be described, particular reference being 5 had to the base runner 53.

A screw eye 98 is secured in the back of the counter-balance 56 and a release cord 99 is secured to said screw eye. Said release cord passes through any suitable number 10 of guiding screw eyes such as 100 backwardly to a release pulley 101 provided as at 102 for the reception of the cord 99. The pulley 101 is rigidly mounted upon the sleeve 103 and on said sleeve is rigidly secured 15 the trip pulley 104. The sleeve 103 is rigidly secured to the shaft 105 and the ends of said shaft are reduced as at 106. The reduced portions 106 work freely in the bearing brackets 107 which are secured to the 20 cross piece 34 by means of screws 108; hence, it is evident that the pulleys 101 and 104 are free to revolve but are kept in longitudinal positions by the large portions of the shaft 105 bearing against the inside of 25 the bearing brackets 107. The trip pulley 104 is provided with a groove 109 for the reception of the reset cord 110, the end of said reset cord being secured to the pulley 104 in any approved manner. A cam nose 30 111 is formed upon the pulley 104 for a purpose hereinafter explained. A latch casing 112 is secured by means of the screws 113 to a block 114 and said block is secured by means of screws 115 to latch brackets 116, said 35 brackets being secured to the cross piece 34 by means of screws 117. The block 114 is placed substantially in line with the pulley 104 and a slot 118 is cut in the cross piece 34 to provide clearance for the cam nose 111. 40 The block 114 is further secured to the cross piece 34 by means of the bolt 119. A trip latch 120 slides freely within the latch casing 112 and is normally pressed downward by means of the spring 121, said latch being 45 prevented from disengagement by the knob 122 screwed therein and working within the slot 123 formed in the latch casing. A latch cord 124 is secured to the knob 122 and the upper end of said cord is secured 50 to the screw eye 125, said screw eye being secured within the front end of the trip lever 126. The trip lever 126 is secured by means of screws 127 to the bearing hub 128 and said hub revolves freely upon the 55 pin 129 mounted in the upper end of the brackets 116. The trip lever 126 extends upwardly and rearwardly and its top end rests just below the guide wire 95. The screw eye 130 is secured near the upper end 60 of the trip lever 126 and a relieving cord 131 is secured to said screw eye. Said cord passes through a hole 132 in the cross piece 34, and the lower end of said cord is secured as at 133 to the trip pulley 104. 65 There is one set of the mechanisms, as

shown in Figs. 8 and 9, and just described, for each of the three base runners of the "in" teams, thus, there is one set for the first base, one set for the second base and one set for the third base, but as shown in 70 Figs. 1, 2 and 8, the pulley corresponding to the pulley 101, for the second base runner is placed as at 134 to the right of the pulley corresponding to the pulley 104. Otherwise, these mechanisms are the same in all respects, and the mechanism for the first base runner is the same as has just been described with reference to the third base runners, thus the pulleys for the first base runner are in all respects similar, respectively, to the 75 pulleys 101 and 104 for the third base runner and similarly located, but the cord 99 which operates the third base runner is joined as at 99^a to the cord 99^b which operates the figure at "home." Release cord 99 80 for the third base runner has been hereinbefore described and the release cords 137 and 138 for the first and second base runners, respectively, are similarly attached and have similar functions. The reset cord 90 110 for the third base runner and home and the reset cords 139 and 140 for the first and second base runners, respectively, are all joined together to the reset cable 141, which extends to the front of the game board and 95 terminates in the reset ring 142.

The means for bringing the ball 97 toward the front of the game board after each displacement therefrom will now be described.

A ball reset guide wire 143 is secured between the front and rear vertical supports 16, in any approved manner, and above the ball guide wire 95 and screw eyes 144 secured in the ball reset bar 145 slide freely upon the wires 95 and 143. Screw eyes 146 100 are secured within the bar 145 and a ball reset cord 147 passes through the screw eye 148 secured within the rear support 16 and said cord extends toward the front of the game board, passing through the screw eye 149 secured in the horizontal pipe section 19. At the front end of the game board the cord 147 passes through the screw eye 150 secured to the front support 16.

The operation of my improved game 115 board is as follows:—

The player of the game is provided with an ordinary baseball bat, and the figures representing the base runners are all hidden as shown in Figs. 1 and 2, at second and 120 third bases and at home.

In Fig. 2 the first base runner is shown elevated but it is also to be hidden at the starting of the game as are the other base runners.

The player is allotted a certain number of hits to strike upon the buffer 70 and when he strikes said buffer, the movement of the pipe 65 caused thereby will be communicated through the belt 74 to the pulley 75, 125 130

and the motion of said pulley will give the bat 91 a movement in the direction of the arrow 151 in Figs. 4; the bat will then strike the ball 97 and depending upon the speed 5 with which the player has struck the buffer 70, the ball 97 will move to different distances toward the rear of the game board. If the ball moves far enough to strike the trip lever 126 and move it backwardly, it is 10 evident that it will also move the trip levers 152 and 153, corresponding to the first and second base runners, but as the effects produced by the movement of these levers are the same as that produced by the lever 126, 15 corresponding to the third and home base runners, only the operation of the lever 126 and its related parts will be explained.

As the lever 126 is moved backwardly, it pulls upon the cord 124, this pulls the 20 trip latch 120 upwardly and releases the cam nose 111; the weight of the counter-balance 56 will then move said counter-balance, the base 54 and the figure 53, representing the third base runner, from the 25 position shown dotted in Figs. 1 and 2 to that shown in Fig. 5. This exposes the third base runner to view and by reason of the connection between the cords 99 and 99^b the figure at "home" is also exposed to 30 view.

It is, of course, to be understood that the base runners at the first and second bases are also exposed because the corresponding levers 152 and 153 have been moved, and furthermore, it is also evident that the reset 35 cords 110, 139 and 140 are hanging loose in order to permit the motion of the pulley 104. When the counter-balance 56 moves, as just described, it will turn the pulleys 40 101 and 104 in the direction of the arrow 154 in Fig. 9.

Should the player of the game strike a light blow upon the buffer 70, the ball may not move far enough to strike the first trip 45 lever 52, in which case no base runner will be exposed to view and no base hit will be counted. If he strikes hard enough to move the base trip lever 152, the first base runner will be exposed to view; if he strikes somewhat harder, the first and second base 50 runners will be exposed to view, and if still harder, the first, second, third, and home base runners will be exposed to view.

In order to reset the game for a new 55 round of play, the operator of the game pulls the reset ring 142. This pulls upon the reset cords 110, 139 and 140 and moves the release and trip pulleys in a direction opposite to that of the arrow 154 in Fig. 60 9 and brings all the cam noses 111 to the left of the trip latch 120 in said figure. The operator then continues to pull upon said reset cords and moves the release pulley 101 and the trip pulley 104 and the corresponding pulleys for the first and second 65

base runners in a counter clock-wise direction from the position shown in Fig. 9, thus pulling upon the relieving cords 131, 155 and 156 and moving the upper end of the trip levers 126, 152 and 153 downwardly 70 from the wire 95. While said trip levers are so held, the operator is then to move the ball reset cord 147 so as to move the reset bar 145 toward the front of the game board, thus restoring the ball 97 to its initial position. The operator is then to move the cord 147 in a reverse direction and return the bar 145 to the position shown in Fig. 2 and finally, the operator is to release the ring 142 and the game board will be set 80 for a new round of play.

I claim:—

1. In a game board, the combination with a cover, of a hole therethrough, a movable figure resting normally below said cover, 85 means for moving said figure through said hole, a buffer, a ball moved by said buffer, a trip lever moved by said ball and connections between said means and said trip lever.

2. In a game board, the combination with 90 a cover and supporting frame, of a baseball diamond on said cover, holes through said cover at the bases of said diamond, a figure movably mounted on said frame subjacent to each of said holes and normally 95 resting below said cover, means for moving said figures through said holes, a buffer, a ball moved by said buffer distances depending upon the speed of said buffer, a plurality of trip levers having ends located in the 100 path of said ball and connections between said trip levers and said figures.

3. In a game board, the combination with a cover and supporting frame, of a baseball diamond on said cover, holes through said 105 cover at the bases of said diamond, a figure movably mounted on said frame subjacent to each of said holes and normally resting below said cover, a buffer and means for moving any number of said figures through 110 said holes, the number depending upon the speed of said buffer.

4. In a game board, the combination with a framework, of a pipe slidably mounted thereon, a buffer mounted upon the end of 115 said pipe, a shaft revolubly mounted upon said framework, a pulley mounted upon said shaft, a bat secured to said shaft, a connection between said pipe and pulley for moving said pulley in one direction, a spring 120 for moving said pulley in the opposite direction, a guide wire supported by said frame, and a ball mounted upon said wire and located to be struck by said bat.

5. In a game board, the combination with 125 a framework, of a pipe slidably mounted thereon, a buffer mounted upon the end of said pipe, a shaft revolubly mounted upon said framework, a pulley mounted upon said shaft, a bat secured to said shaft, a connec- 130

- tion between said pipe and pulley for moving said pulley in one direction, a spring for moving said pulley in the opposite direction, a guide wire supported by said frame, a ball 5 mounted upon said wire and located to be struck by said bat, a slot in said bat embracing said wire and an end piece on said bat for limiting the movement thereof.
6. In a game board, the combination with 10 a framework and a trip lever mounted thereon, of a latch operated thereby, bearings mounted upon said framework, a shaft revolvably mounted in said bearings, a trip pulley mounted on said shaft and controlled by 15 said latch, a cam nose on said pulley for engaging with said latch to lock said pulley and a connection between said pulley and said lever whereby said lever is moved by
7. In a game board, the combination with 20 a framework and a trip lever mounted thereon, of a latch operated thereby, bearings mounted upon said framework, a shaft revolvably mounted in said bearings, a trip 25 pulley mounted on said shaft and controlled by said latch, a cam nose on said pulley for engaging with said latch to lock said pulley, a release pulley mounted upon said shaft, a movable figure mounted upon said frame, a 30 connection between said release pulley and said figure and a reset cord connected to said trip pulley and extending to the front of said framework.

In testimony whereof I affix my signature. 35
GEORGE A. LOWREY.

Copies of this patent may be obtained for five cents each, by addressing the "Commissioner of Patents,
Washington, D. C."
